UNITED STATES PATENT OFFICE.

JOHN F. WAY, OF NORWICH, CONNECTICUT.

STARTING GAUGE FOR LOOMS.

Application filed October 18, 1924. Serial No. 744,368.

To all whom it may concern:

Be it known that I, JOHN F. WAY, a citizen of the United States, residing at Norwich, in the county of New London and 5 State of Connecticut, have invented certain new and useful Improvements in Starting Gauges for Looms; and I do hereby declare the following to be a full, clear, and exact description of the invention, such as 10 will enable others skilled in the art to which it appertains to make and use the same.

This invention has for its object the provision of indicating means for use in looms 15 to insure accurate positioning of the weft line or fell when restarting the loom after the same has been stopped to remedy a fault so as to insure an even and uniform weaving without showing any lay mark which 20 would tend to mar the texture of the finished fabric.

Other objects and advantages will be apparent and suggest themselves as the nature of the invention is understood.

25 While the drawings illustrate an embodiment of the invention it is to be understood that in adapting the same to meet different conditions and requirements, various changes in the form, proportion and 30 minor details of construction may be resorted to without departing from the nature of the invention.

Referring to the accompanying drawings forming a part of the specification,

35 Figure 1 is a fragmentary view of a loom provided with indicating means embodying the invention,

Figure 2 is a top plan view,

40 Figure 3 is an enlarged sectional view of the indicating means,

Figure 4 is an enlarged top plan view of the device,

Figure 5 is a sectional view showing the device folded, and

45 Figures 6 and 7 are detail views.

Corresponding and like parts are referred to in the following description and designated in the several views of the drawings by like reference characters.

50 The numeral 1 denotes the breast beam of a loom and 2 the batten, and in accordance with the present invention the indicating means or gauge is mounted upon the breast beam 1 and comprises a base plate

55 3 provided with a housing 4 which is adapted to receive and protect the indicator. An

arm 5 has a limited sliding movement on the base plate 3 and is guided in its movements and prevented from displacement. An arm 6 is pivoted at one end to the outer end of the arm 5 and is limited in its movement by stops 7. A plate 8 is adjustably connected to the pivoted arm 6 and is provided at its outer or free end with a casing 9 which encloses a gearing and a rack bar 10 which is slidable through opposite ends of the casing and has a cross piece 11 at its outer end to which gauge pins 12 are attached. The rack bar 10 is in mesh with a pinion 13 fast to a shaft 14, the latter having a gear wheel 15 fast thereto which is in mesh with a pinion 16 fast to a shaft 17. The shafts 14 and 17 project beyond the top of the casing 9 and their projecting ends are provided with hands 18 and 19 respectively. The ratio of the gearing is such that the shaft 17 makes six complete revolutions to one revolution of the shaft 14, hence the hand 19 makes six revolutions to one revolution of the hand 18. An indicating 70 mark 20 coacts with the hand 19 hence a very slight movement of the rack bar 10 is amplified by the indication of the hand 19 with the result that any slight variation 75 when readjusting the cloth preliminary to restarting the loom is readily determined with the result that accuracy is assured in the fell or weft line when again starting the loom.

The pivotal movement of the arm 6 admits of folding the same on the arm 5 and the sliding movement of the latter admits of introducing the indicating or gauge means within the housing 4 which protects and shields the same. The construction is such as to admit of the indicator being located so as to operate above or beneath the fabric and this is of material advantage because of the different makes of looms.

What is claimed is:

1. A starting gauge for looms comprising a housing, an arm slidably mounted into and out of said housing, a supporting member adjustably mounted on said arm, and a gauge carried by said supporting member, said supporting member being adapted to be adjusted relatively to said arm to permit introduction of the gauge carried thereby into the housing for protection when not in use.

2. A starting gauge for looms the same comprising a housing, a member slidably in-

to and out of the housing, and an arm having a limited pivotal movement with reference to said member and provided at its free end with a gauge, said arm and gauge being adapted to be folded on said member and to be disposed within the housing when the device is not required for immediate use.

3. A starting gauge for looms the same comprising a housing, an arm slideable into and out of the housing, a second arm pivoted to the sliding arm, and a gauge having adjustable connection with the pivoted arm, said second arm and gauge being adapted to be folded on said first mentioned arm and to be located within the housing when not required for immediate service.

4. In a starting gauge for looms, a casing a rack bar slideable through the ends of the casing and having a cross piece at its outer end, gauge pins projecting from said cross piece, shafts journaled on said casing, a hand secured to each shaft, gearing connect-

ing said shafts and adapted to rotate them at different speeds, one of said shafts being geared to said rack bar, and said casing having a mark thereon to coat with one of said hands.

5. In a starting gauge of the character specified, a base plate, a housing thereon, an arm having slideable connection with the base plate, a second arm pivoted to the sliding arm, a plate having adjustable connection with the pivoted arm, a casing at the outer end of the said plate, a rack bar slideable through the ends of the casing and having a cross piece at its outer end, gauge pins projecting from the cross piece, parallel shafts, speed gearing connecting said shafts to each other and to the rack bar, and hands attached to the projecting ends of the shafts and adapted to coat with an indicating mark on the casing.

In testimony whereof I affix my signature.

JOHN F. WAY.
